UNITED STATES PATENT OFFICE.

EARL L. MILLER, OF OVERBROOK, KANSAS.

TIMER-BRUSH.

1,377,361.

Specification of Letters Patent. Patented May 10, 1921.

Application filed January 14, 1919. Serial No. 271,035.

To all whom it may concern:

Be it known that I, EARL L. MILLER, a citizen of the United States, residing at Overbrook, in the county of Osage and State 5 of Kansas, have invented new and useful Improvements in Timer-Brushes, of which the following is a specification.

This invention relates to contact brushes for timing devices of internal combustion 10 engines, the main objects being to provide a brush of simple construction, which may be manufactured at a minimum cost; to protract the life of the device; and to obtain the most efficient contact, while minimizing 15 the danger of injury to the brush from back firing.

I have herein described and explained the best embodiment of my invention at present known to me, indicating in my claims the 20 scope and essentials of the invention in its various phases and aspects.

In the accompanying drawings, I have shown the invention as embodied in a form which is most economical of construction, 25 and which insures the attainment of all the other desired objects above mentioned.

In this embodiment the invention comprehends as driving element for the brush a sleeve which is preferably bent into cylindrical form, and which is provided with a longitudinally arranged diametrically extending flange, which, in this instance, is integral with the sleeve, being formed by bending the end of the material of which 30 the sleeve is formed, outwardly. This sleeve is provided with a spring contact arm, extending therefrom in a substantially spiral direction, and having at its outer or free end a hardened metal contact element. The 35 flange just mentioned is slotted longitudinally to provide restraining means for the spring arm, which means prevents any substantial transverse bending or shifting of said arm, and also limits the movement 40 thereof in a radial direction.

In the most complete embodiment of the invention, (as herein shown), an auxiliary extended sustaining element is provided, arranged parallel to, but independent of, the 45 spring arm, for a substantial distance along the outer face of the latter. As shown herein, this auxiliary element is preferably resilient, and is itself controlled by the restraining means just described.

50 In the drawings, Figure I, is a plan view

of a timer equipped with my improved contact brush.

Fig. II, is a detail perspective view of the brush member itself, in this instance, in its preferred form.

Referring to the drawings, the timer casting is indicated at 10, the contact segments at 11, and the conductor terminals at 12. These may be of the usual or any preferred construction: As shown, the timer casting 10 and its associated parts 11, 12, etc., are of the familiar form heretofore used on Ford automobiles. The timer shaft is shown at 13, and is revolved in the ordinary manner. Said shaft is cylindrical, as shown, 65 and is adapted to receive and rotate the brush which constitutes the present invention. This brush includes as driving element a sleeve 14, of novel construction, being preferably formed from a strip of sheet 70 metal bent into cylindrical shape, and of a size to fit the shaft 13. In this embodiment of the invention, one end of the strip is bent and extends outwardly from the sleeve to provide an elongated radially disposed 75 flange 15, which is provided with a slot 16. A spring arm 18 is mounted on and extends 80 from the round sleeve, being, in this instance, attached or secured to the sleeve against its rounded surface through the medium of a rivet 17, or other fastening device, 85 at one extremity of said arm. The resiliently flexible spring contact arm 18 diverges tangentially from the rounded surface of the sleeve 14, against which it is mounted, and 90 extends on outward from and around the sleeve, preferably in a sort of curving, spiral fashion, as already noted. The tangential divergence of the spring arm 18 permits it 95 to flex easily and smoothly to and from and against the rounded surface of the sleeve 14, without sharply localized stress or strain. In Fig. I of the drawing, the arm 18 is shown flexed against the round sleeve from the point of attachment of said arm at 17 100 around to the point of divergence thereof over a substantial distance. The diverging spring arm 18, passes freely through the slot, at either edge of the arm, 16, in the flange 15, the metal at the ends thereof preventing 105 any substantial transverse shifting of the arm, while the overhanging metal at the outer (or of the portion thereof extending from and around the sleeve) face of the slot restrains or limits outward movement or 110

play of the arm in a radial direction. The arm 18 extends on outward from and around the sleeve 14 so as to come into approximately tangential relation to the surface of the coöperating timer casing 10, and has secured thereto at its free end a hardened metal contact element or wiper 19, which is adapted to engage the inner surface of the casing 10 and wipe over the segments 11, in the usual manner. The auxiliary sustaining element 20, (in this instance a leaf spring), lies outside of and parallel to the arm 18 in contact with but independent of the arm and extends around the sleeve 14 along the outer face of said arm throughout an extended portion of the length thereof in the region of its contact with and divergence from said sleeve, said element being secured to the sleeve 14, preferably by the fastening device 17, which, in this instance, secures the arm to the sleeve. The depth of the slot 16, in a radial direction, is preferably sufficient to allow some radial play of the arm 18, even when the auxiliary sustaining element 20, is employed. The sleeve 14, is provided with a notch 21, for the reception of the pin 22, carried by the shaft 13, which serves as means for removably securing the sleeve upon the shaft.

It will be noted that the spring arm 18, at its inner extremity, extends from, or is rigidly or fixedly attached to, the sleeve, but that the restraining means (in this instance the slotted flange) carried by the sleeve, is located at some distance from the region of rigid extension, or rigid attachment, of the arm with relation to the sleeve, and does not constitute an absolutely rigid connection. This organization minimizes the tendency to crystallize, which is manifested by the spring arm, at, or near, the region where it extends from or is rigidly attached to, the sleeve. The employment of the auxiliary sustaining element 20 carried by the sleeve enhances this desirable feature and also prevents the buckling of the main spring arm, when back firing occurs. This element 20 acts, in a word, to ease, diffuse, and control the variations of stress and strain in the contact arm 18.

It will also be noted that the slot 16, of the restraining device for the arm 18, is, in the instance shown, completely inclosed, so as to extend across the entire width of the arm 18, and, in the complete embodiment, also entirely across the auxiliary spring. This, however, is a detail which may be varied, as it is only necessary for the restraining device to overlie, overhang, or engage a sufficient portion of the spring arm to insure the proper limitation of the play in a radial direction. Furthermore, in the instance shown, the restraining device is, for reasons of economy, formed integral with the sleeve, and the arm 18, is shown as

non-integral with the sleeve. These and other details, however, may be varied, without departing from the spirit of the invention.

The invention as shown and described, provides an exceedingly efficient and inexpensive timer brush which may be readily secured to or removed from the timer shaft, permitting a broken or damaged brush to be replaced at a nominal cost. 75

I have above referred to the use of my invention on automobiles for the reason that it is of the greatest advantage in this field of use. For instance, the timer brush heretofore employed on one widely used type 80 of car had for its contact arm a heavy pivoted lever with a roller contact element at one end urged into contact with the timer casing by a helical tension spring acting on the other end of the lever. This contact arm 85 did not maintain continuous, uniform contact with the interior of the timer casing, but would lose and regain contact from time to time (owing to its own inertia, and the vibration of the engine and of the vehicle) 90 in such a way as to hammer and wear the inner surface of the casing into a succession of bumps and hollows. This condition of the casing still further accentuated the mal-operation that gave rise to it, and made the 95 sparking action of the timer most irregular and unsatisfactory.

With its light, flexibly resilient spring contact arm, my timer brush not only maintains continuous good, firm, even contact 100 with the timer casing,—without danger of hammering or injury thereof,—but even acts to smooth out and restore to operating efficiency a timer casing that has been more or less ruined by a brush of the old type. 105 This maintenance of firm contact by my brush is due to the easy, smooth flexure of the spring arm 18 to, from, and against the rounded surface of the driving element 14, which not only tends of itself to minimize 110 breakage through "fatigue" crystallization of the metal (even without the restraining means at 16), but also facilitates the maintenance of adequate contact pressure between contact 19 and timer casing 10 with a substantially tangential relation of brush arm and casing. This latter relation is of importance to smooth, continuous contact and uniform sparking,—as well as to the avoidance of buckling of the arm and injury to 115 the casing surface when backfire occurs,— quite apart, again, from the effect of the sustaining and restraining elements 20 and 16 in this respect.

The invention is susceptible of various 125 changes in its form and proportions and minor details of construction, and the right is herein reserved to make such changes as properly fall within the scope of the appended claims.

Having thus described my invention, I claim:

1. A timer brush comprising a rotary driving element; a spring arm mounted on and extending from and around said driving element, for making contact with the contact segments of a timer casing; and means carried by said driving element for restraining outward movement of the portion of said arm extending from and around said driving element.
2. A timer brush comprising a sleeve; a spring arm rigidly connected to and extending from said sleeve; and restraining means also extending from the sleeve for freely engaging said arm, to limit the radial play thereof, at a distance from the region of rigid connection between the arm and the sleeve.
3. A timer brush comprising a sleeve; a spring arm extending from said sleeve, and having its outer end disposed for contact with the contact segments of a timer casing; and restraining means carried by the sleeve, said means freely overhanging the arm and being adapted to limit the radial play thereof, and to prevent substantial transverse shifting of the arm.
4. A timer brush comprising a sheet metal sleeve with integral overhanging restraining means in longitudinal flange form extending outward therefrom; and a spring arm extending from said sleeve within said overhanging restraining means, and having its outer end disposed for contact with the contact segments of a timer casing.
5. A timer brush comprising a sleeve; a spring arm for making contact with the contact segments of a timer casing attached to said sleeve; and restraining means for said arm extending outward from said sleeve at either edge of said arm, and also overhanging the latter at either edge thereof.
6. A timer brush comprising a sleeve with a restraining portion affording a slot extending lengthwise of the sleeve and overhung by said portion; and a spring arm extending from said sleeve through said slot and having its outer end disposed for contact with the contact segments of a timer casing.
7. A timer brush comprising a strip of metal in the form of a non-continuous sleeve with an integral longitudinally radial flange extending outward at one end of the strip, said flange being provided with a longitudinal slot; and a spring arm rigidly connected with the sleeve and extending through said slot, said arm having its outer extremity disposed for contact with the contact segments of a timer casing.
8. A timer brush comprising a sleeve; a spring arm extending from said sleeve; and an elongated auxiliary sustaining element for said arm extending from said sleeve in the same direction as said arm.
9. A timer brush comprising a sleeve; a spring arm extending from said sleeve; and an elongated auxiliary sustaining spring extending parallel to and outside of said arm.
10. A timer brush comprising a sleeve; a spring arm extending from said sleeve; an elongated auxiliary supporting element extending in contact with said arm; and restraining means for said arm and said auxiliary element carried by the sleeve, but independent of the main connection between the sleeve and the auxiliary element.
11. A timer brush comprising a strip of metal in the form of a non-continuous sleeve with an integral longitudinally radial flange extending outward at one end of the strip, said flange having a longitudinal slot; a spring arm rigidly extending from the sleeve and passing through said slot, the outer extremity of said arm being disposed for contact with the segments of a timer casing; and an auxiliary spring secured to the sleeve and also extending through said slot.
12. A timer brush comprising a round driving element; and a resiliently flexible spring arm mounted against the rounded surface of said element diverging and extending therefrom tangentially and spirally outward around the element, so as to flex easily and smoothly to and from and against said rounded surface, without sharply localized stress or strain.
13. A timer brush comprising a round driving element; and a resiliently flexible spring arm mounted on said element diverging tangentially from its rounded surface and extending outward from and around the element so as to come into approximately tangential relation to the surface of a cooperating timer casing, and having a contact part for engagement with such casing; so that said spring arm shall flex easily and smoothly to and from and against the rounded surface of said element without sharply localized stress or strain, and that said contact part shall maintain continuous good contact with said casing without danger of hammering or buckling.
14. A timer brush comprising a round driving element; a resiliently flexible spring arm mounted on said element diverging tangentially from its rounded surface and extending from and around the element, so as to flex easily and smoothly to and from and against said rounded surface, without sharply localized stress or strain; and an auxiliary sustaining element extending around said driving element along the other face of said spring arm in the region of its contact with and divergence from the driving element, so as to ease and diffuse the variations of stress in said spring arm.

15. A timer brush comprising a round driving element; a resiliently flexible spring arm mounted on said element diverging tangentially from its rounded surface and extending from and around the element, so as to flex easily and smoothly to and from and against said rounded surface; an auxiliary resilient sustaining element for said spring arm carried by said driving element and extending around the same along the face of said spring arm in the region of its contact with and divergence from the driving element; and means carried by said driving element for restraining radial movement of the portion of said spring arm extending from said driving element.

16. A timer brush comprising a round driving element; a resiliently flexible spring arm mounted on said element diverging tangentially from its rounded surface and ex-

tending from and around the element, so as to flex easily and smoothly to and from and against said rounded surface; an auxiliary resilient sustaining element for said spring arm carried by said driving element and extending around the same along the face of said spring arm in the region of its contact with and divergence from the driving element; and means carried by said driving element for restraining radial movement of the portion of said spring arm extending from said driving element.

In testimony whereof I affix my signature.

EARL L. MILLER.
